(57) **CLAIM**

The ornamental design for a bottle, as shown and described.

DESCRIPTION

FIG. 1 is a perspective view of a bottle showing my new design;

FIG. 2 is a front elevational view, the rear and side views being identical, thereof; and,

FIG. 3 is a top plan view thereof.

The broken line showing of the cap and brush assembly in FIGS. 1-3 is for illustrative purposes only and forms no part of the claimed design.
